UNITED STATES PATENT OFFICE.

FRANKLIN S. FRISBIE, OF BOSTON, MASSACHUSETTS.

DESIGN FOR A BADGE.

No. 38,298.

Specification for Design.

Patented Oct. 30, 1906.

Application filed October 12, 1905. Serial No. 282,522. Term of patent 7 years.

To all whom it may concern:

Be it known that I, FRANKLIN S. FRISBIE, a citizen of the United States, residing at Boston, in the county of Suffolk and State of Massachusetts, have invented a new, original, and ornamental Design for a Badge.

I claim—

The ornamental design for a badge, as shown.

FRANKLIN S. FRISBIE.

Witnesses:

JOHN H. GRIGGS,
HERBERT C. COY.
